UNITED STATES PATENT OFFICE.

JOHN C. MANLEY, OF CHICAGO, ILLINOIS, ASSIGNOR TO THE INVENTORS DEVELOPMENT COMPANY, OF CHICAGO, ILLINOIS.

LAMP-LOCKING DEVICE.

1,032,618.

Specification of Letters Patent. Patented July 16, 1912.

Application filed April 12, 1910. Serial No. 555,083.

To all whom it may concern:

Be it known that I, JOHN C. MANLEY, a citizen of the United States, residing at Chicago, in the county of Cook and State of Illinois, have invented a certain new and useful Improvement in Lamp-Locking Devices, of which the following is a full, clear, concise, and exact description, reference being had to the accompanying drawings, forming a part of this specification.

My invention relates to locking devices, and more particularly to lamp locking devices, and has for its object the provision of improved means for preventing the unauthorized withdrawal of such articles as incandescent lamp globes from their sockets.

My invention in its preferred form contemplates an element fixed relatively to the socket, co-acting with another element placed upon the lamp, and a suitable sealing or locking means for uniting the two members together.

The invention further contemplates devices independently of the sockets for preventing unauthorized withdrawal of globes.

I will describe my invention more in detail by reference to the accompanying drawing, illustrating several forms of carrying out the invention, in which—

Figure 1 is a view of an incandescent lamp globe provided with my improved locking means, Figs. 2 and 3 are details of a construction utilized in Fig. 1, Fig. 4 is a key which I may employ, Fig. 5 illustrates another form of the invention, Fig. 6 shows a multiple lamp locking device, Fig. 7 shows locking devices for locking the lamps independently of the sockets, Fig. 8 shows another form of carrying out the invention illustrated in Fig. 1, and Figs. 9 and 10 are detail views of the lock set forth in Fig. 1.

Referring more particularly to Figs. 1, 2, 3 and 4 I show a socket 1, to which is attached a locking member 2, which locking member is shown in its developed condition in Fig. 2. A second locking member 3, shown in detail in Fig. 3, is provided, which locking member is expansible and has its interior diameter increased or diminished when the key 4 operating in a slot 5 is rotated. The key 4 when inserted can be rotated to expand the member 3, or rotated in such a manner as to contract said member, whereby to press it in position about the hub

6 of the lamp, which lamp has the ordinary 55 glass globe 7, with a screw threaded portion 8, adapted to enter the socket 1.

In carrying out the invention the member 2 is fastened to the socket through the agency of the ring 9, and the bent arms 60 10—10 thereof are inserted against the hub 6 under the element 3. The arms 10 have pins or projecting points 11—11, which indent the hub 6 of the lamp when the member 3 has been contracted by the key 4. Thus, after the arms 10 have been inserted under the element 3 and said element has its key turned locking same, the pins 11 are pressed into the hub 6, and so hold the lamp in position so long as the key is not rotated to 70 unlock the element 3.

In Figs. 9 and 10 I show in detail the locking mechanism of Fig. 1, and this locking mechanism is associated with the band 3 as follows: The ends of the band 3 are clamped between distance pieces 24 and 25 and a hood 26 surmounts the working parts. The hood 26 carries the plate 27 having an aperture 5 therein for the key 4 and lugs 28, 28 are provided upon the hood 26. A rotatable 75 plate 29 having a slot 30 for engagement by the key is provided between the distance pieces 25 and the lugs 28. The plate 29 has inclined runways 31, 31 as shown more clearly in Fig. 10 which have an indentation 32 to receive the lugs 28 when the device is locked. When the key is inserted to rotate the plate 29 into the position of Fig. 9, the devices 24 are pressed inwardly against the lamp whereby the prongs 11 engage the 85 lamp socket and hold it in place. To remove the lamp, the plate 29 is rotated so that the inclined runways 31 are not under the lugs 28 and this leaves sufficient room to disengage the prongs 11 and disengage the band 3. 95 It will be seen from this that the lamp 7 cannot be withdrawn from the socket 1, except by an authorized attendant in possession of the key 4.

In Fig. 5 I show an element 12, fastened 100 to the socket 1, and a ring 13, which ring is placed about the hub 6. A screw threaded arm 14, is then screwed through the ring 13, and partially into the hub 6. A lock 15 then serves to clamp the two members 14 and 12 105 together, and hold them in position so that the lamp cannot be unauthorizedly withdrawn. I find it of great advantage also to

have multiple means for holding in position a plurality of lamps, and this is shown more clearly in Fig. 6, where I use a ring 13 and an element 23, similar in its general outlines to element 14 of Fig. 5, except that it does not have the upturned bent portion. Hangers 16 are then provided on some fixed place, either with the socket or apart from the socket, and a chain 17 runs through the eyelets 23 and through the hangers 16, and is then locked by a suitable lock 15. This will indicate the great facility with which a plurality of lamps may be locked in position and the chain or cord suitably held, so as not to present an unsightly appearance.

I do not want it understood, of course, that the elements 2, 12 or 16 need to be associated directly with the sockets, as they can be mounted in a fixed position in any suitable manner.

In Fig. 7 I show a further embodiment of the invention in that I do not utilize the sockets or any fixed portion of the mounting thereof in connection with the lamp locking devices, and in this instance in connection with the lamp 7 I use the ring 13 and the eyelets 18, in that they screw through the rings 13 and indent themselves partially into the hub 6, but not having the bent form as shown in Fig. 5. These arms or pins 18 are then held together by means of the lock 15, as shown. Any number of lamps may be thus secured without the use of a fixed locking device.

In Fig. 8 I show a further form of carrying out the invention, in that in connection with the ring 13 and pin 14, I use a second ring 19, mounted upon the socket in association with a similar pin 20, both of which pins or eyelets are then suitably held together by means of a wire 21 and seal 22.

It will be understood, of course, that I have here illustrated several forms of carrying out the invention in order to set forth that the invention is capable of a great variety of modifications. I do not wish to imply that the modifications shown are the only ones of which the invention is capable, nor do I wish to limit myself to the precise details as set forth, as many modifications

may be made by the substitution of equivalents, and the same results obtained, but

Having thus described the invention in some of its salient embodiments, what I claim as new and desire to secure by Letters Patent is:

1. The combination with a plurality of lamp sockets and lamps therefor, of a locking member for each lamp, and means for securing said locking members together, each of said locking members having means adapted when actuated to indent itself in the lamp shell to hold the lamp in position.

2. The combination with a lamp socket and a lamp therefor, of locking means for preventing the unauthorized withdrawal of said lamp, said locking means including a ring about the metal portion of said lamp, and a prong adapted for indenting said lamp and being indented in said lamp by the action of said ring, and means to hold said prong in position.

3. The combination with a lamp socket and a lamp therefor having a thin metal shell, of means to prevent the unauthorized withdrawal of said lamp from said socket, said means including a pointed prong extending through a stationary member and adapted when actuated to dent the thin metal shell of the lamp and remain in the dent whereby said lamp may be held in place within the socket.

4. The combination with a lamp socket and a lamp therefor having a thin metal shell, of locking means to prevent the unauthorized withdrawal of said lamp from said socket, said means including a pointed prong extending through a stationary member and adapted when actuated to dent the thin metal shell of the lamp and remain in the dent whereby said lamp may be held in place within the socket.

In witness whereof, I hereunto subscribe my name this fifth day of April A. D., 1910.

JOHN C. MANLEY.
